BARBER'S SCISSORS

Maurice Hammond, Liberty Mills, Ind.

Application July 24, 1942, Serial No. 452,177

2 Claims. (Cl. 30—233)

The invention relates to hair cutting scissors and its chief object is to provide means on the outer face of the outer blade of the scissors to support the hair as it is cut and which immediately releases the severed parts so that they fall out of the way.

Other objects and advantages will appear hereinafter.

The invention is illustrated in the accompanying drawing in which

Figure 1 is a plan view of a pair of scissors having the invention applied thereto and Fig. 2 is a cross-section on line 2—2 of Fig. 1.

Referring to the illustrative embodiment of the invention, 10 represents a pair of scissors having the cooperating cutting blades 11, 12 pivotally connected at 13. The innermost blade 11 is arranged with the usual handle 14 and finger loop 15 and the outer blade 12 has a similar handle 16 and finger loop 17 and in addition a curved extension 18 on the loop 17 for engagement by a second finger of the hand.

A thin toothed bar 19 is removably attached to the outer face of the outer blade 12 by the screws 20. The teeth on the bar are relatively fine and of such length that they will project slightly above the cutting edge of the blade 12 with the slots extending below the said edge a sufficient distance to form channels on the face of the blade into which the hairs that are engaged and supported between the teeth will drop when severed and thereby be conducted away from the cutting edge of the blade and avoid clogging of the teeth at the cutting edge. Slots 21 may be formed in the bar 19 to provide adjustment of the bar relatively to the cutting edge of the said blade 12, especially after the blade has been sharpened.

In use the scissors in open condition is inserted into the hair with the toothed bar-carrying blade outermost. The hair will engage in the relatively shallow slots between the teeth and above the cutting edge of the blade and be supported in cutting position thereby. When the blades are closed on one another the hairs are cut off and the severed portions slide down the slots in the bar between the teeth and thus are automatically removed from the blades.

What I claim is:

1. A hair-cutting scissors comprising a pair of cutting blades pivoted together, a thin, fine-toothed bar attached to the outer face of the outer blade and adjustable toward the cutting edge of said blade, the teeth projecting slightly above the cutting edge of the outer blade to support the hair and the slots between the teeth extending below said edge and forming channels to receive the severed hairs and conduct them downwardly.

2. A hair-cutting scissors comprising a pair of cutting blades pivoted together, a thin, fine-toothed bar attached to the outer face of the outer blade, the teeth projecting slightly above the cutting edge of the outer blade to support the hair and the slots between the teeth extending below said edge and forming channels to receive the severed hairs and conduct them downwardly, the bar having transverse slots therein and screws extending through the slots and into the adjacent blade to afford adjustment of the toothed edge of the bar relatively to the cutting edge of said blade.

MAURICE HAMMOND.
